Primary Examiner — Cynthia Ramirez*Assistant Examiner* — Tamara L Hahn(74) *Attorney, Agent, or Firm* — McDonald Hopkins LLC(57) **CLAIM**

The ornamental design for a roller shield device, as shown and described.

DESCRIPTION

FIG. 1 is a perspective view of an embodiment of a roller shield device showing our new design;

FIG. 2 is a first side view thereof;

FIG. 3 is a second side view thereof;

FIG. 4 is a back side view thereof;

FIG. 5 is a front side view thereof;

FIG. 6 is a top view thereof;

FIG. 7 is a bottom view thereof; and,

FIG. 8 is a perspective view of the roller shield device attached to a paint roller assembly.

The broken lines in FIG. 8 depict environment that form no part of the claimed design.
